(57) **CLAIM**

The ornamental design for a circular saw with cover, as shown and described.

DESCRIPTION

FIG. 1 is a top front perspective view of a circular saw with cover showing our new design;

FIG. 2 is a bottom perspective view thereof;

FIG. 3 is a front side plan view thereof;

FIG. 4 is a right side plan view thereof;

FIG. 5 is a back plan view thereof;

FIG. 6 is a left plan view thereof;

FIG. 7 is a top plan view thereof; and,

FIG. 8 is a bottom plan view thereof.

The broken lines in the drawings depict portions of the circular saw with cover that form no part of the claimed design.

1 Claim, 6 Drawing Sheets(56)
